UNITED STATES PATENT OFFICE.

ALFRED F. MCCOLLUM, OF BLOOMSBURG, PENNSYLVANIA, ASSIGNOR OF THREE-FIFTHS TO JAMES MAGEE, 2d, OF BLOOMSBURG, PENNSYLVANIA.

SHUTTLE FOR SEWING-MACHINES.

1,398,872.

Specification of Letters Patent. Patented Nov. 29, 1921.

Application filed June 28, 1918. Serial No. 242,475.

To all whom it may concern:

Be it known that I, ALFRED F. MCCOLLUM, a citizen of the United States, residing in Bloomsburg, Columbia county, State of Pennsylvania, have invented Shuttles for Sewing-Machines, of which the following is a specification.

One object of my invention is to provide means for so supporting and guiding the shuttle of a sewing machine as to prevent its displacement in the shuttle race by reason of wear of the guide and also of the shuttle driver, and the consequent missing of stitches.

Another object of the invention is to provide novel means for compelling the shuttle to oscillate and at all times remain in, a circular path independently of and without regard to any supporting action possessed by the shuttle driver; the arrangement of parts for attaining this object being relatively simple and of such a nature as to be easily applied to new machines as well as those already in use.

These objects and other advantageous ends I secure as hereinafter set forth, reference being had to the accompanying drawings in which,

Figure 1 is a side elevation of a shuttle and certain of its associated parts, to which my invention has been applied;

Fig. 2 is an elevation of that side of the shuttle race and shuttle opposite that of Fig. 1;

Fig. 3 is a vertical section on the line 3—3, Fig. 2;

Fig. 4 is a fragmentary cross section on the line 4—4, Fig. 2;

Fig. 5 is a front elevation of one side of a shuttle constructed according to my invention; and

Fig. 6 is an elevation of the shuttle-retaining ring intended to coöperate with the shuttle shown in Fig. 5.

In the above drawings, 1 represents the top of a sewing machine having an opening in which is mounted a removable needle plate 2 having a slot elongated from front to rear for the passage of the needle 3. Mounted transversely in this slot below the plane of the plate 2 is a roller 4 designed to support the lower end of the needle against bending under the action of the fabric or other material operated on and also to guide and sup-

port the thread between the bobbin and said material.

Above the thread plate 2 are mounted the feed foot 5 and the presser foot 6 both of which coact in the ordinary manner with the needle plate 2 to alternately hold and longitudinally feed the material to be sewed. Beneath the top 1 is mounted the shuttle race 7 held to the frame of the machine by screws 8 and provided with the customary circular guideway for the shuttle 9. This latter is designed to oscillate in said guideway under the action of the oscillating driver 10 whose extremities normally engage the corresponding extremities of the shuttle.

For removably retaining the shuttle in its guideway provided by the shuttle race, a ring 11 (Fig. 6) is ordinarily employed and it is made with two holes 12 in its opposite sides for the reception of a pair of pins 13 projecting from the adjacent face of the shuttle race. While these pins ordinarily have been made to closely fit said holes, according to my invention the latter are from fifty to one hundred per cent. larger in diameter than the pins so as to allow of a slight adjustment of the ring 11 relatively to the shuttle race. The ring is yieldingly held in position by a forked spring 14 of flat material whose two arms engage it immediately adjacent the openings 12 and which is removably held to the race by a screw 15.

One feature of my invention resides in forming that face of the shuttle under the ring 11 with a circular groove of angular cross section formed by extending its concentrically curved edge substantially at right angles to its plane and in providing the ring with a rib 17 of angular cross section designed to closely fit into this groove, so that the shuttle, instead of depending upon the driver to hold it in position in its guideway, is at all times compelled to move and is retained in a circular path by the ring 11. While the driver as originally constructed accomplishes this same object with reasonable certainty before wear occurs, I have found that under operating conditions the wear of the guideway of the shuttle race as well the wear between the driver and the shuttle causes such an amount of lost motion as permits said shuttle to move out of its circular path so that as a

consequence the machine will sooner or later begin to miss stitches.

By my invention however, the rib on the ring 11 at all times maintains the shuttle 5 in the required position in the shuttle race and even though there should be considerable wear between these two structures, it is possible to adjust the ring by loosening the screw 15 so as to again properly position the shuttle,—the play between the walls 10 of the openings 12 and the pins 13 permitting of the necessary relative movement of the ring.

From the above description it will be 15 seen that I am enabled to effectually prevent the missing of stitches by the machine after the parts have been subjected to a certain amount of wear and have provided means whereby, even if abnormal wear has 20 occurred, it is possible to so adjust the shuttle-holding ring as to still cause the shuttle to operate in a circular path;—it being obviously immaterial as to which of the two members comprised by the shuttle 25 and the shuttle-retaining ring is provided with the rib 17. It will be noted from Fig. 4 that one wall of the groove in the shuttle is inclined so as to be continuous with or form part of the inclined surface

of the shuttle body so that under conditions of use the thread will not lay or be held in said groove but moves freely around the shuttle without danger of catching or cutting.

Since with the loose connection provided by the pins 13 and the larger openings 12 in the ring 11, the shuttle is free to automatically adjust itself in its guideway to that position in which it runs most easily, it will be understood that a machine 40 equipped with my invention requires less power for its operation than would ordinarily be the case.

I claim:

The combination of a shuttle race having a guideway; a shuttle operative in the guideway and having a relatively thin edge portion extended substantially at right angles to form a circularly curved groove adjacent its periphery, one wall of the groove 45 being inclined and substantially continuous with the correspondingly inclined surface of the shuttle body; with an annular retaining member having a guiding rib of 50 angular cross section slidably fitting said 55 groove of the shuttle.

In witness whereof I affix my signature.

ALFRED F. McCOLLUM.
